UNITED STATES PATENT OFFICE.

JAMES MARSDEN, OF WIGAN, ENGLAND.

SEWING-MACHINE.

1,394,039.

Specification of Letters Patent. Patented Oct. 18, 1921.

Application filed February 1, 1921. Serial No. 441,669.

To all whom it may concern:

Be it known that I, JAMES MARSDEN, subject of the King of Great Britain, residing in Wigan, in the county of Lancaster and 5 Kingdom of England, have invented certain new and useful Improvements in or in Connection with Sewing-Machines, of which the following is a specification.

This invention has reference to sewing 10 machines, and more especially to the type in which the needle thread is carried around or interlooped with the under thread by a shuttle having either an oscillating or a continuous rotary movement in a shuttle race, 15 the said under thread being contained in a case around which the loops of needle thread are carried by the shuttle.

The object of the invention is to provide 20 an arrangement by which without altering, or materially altering, the construction of the machine, the spool or metallic reel for the under thread, can be made larger than heretofore, so as to accommodate a much greater supply of under thread, and thus 25 avoid having to rewind the metallic reel, or replace an empty bobbin by a full one into the shuttle, so frequently as has been customary. A large bobbin for the under thread is, of course desirable to avoid stopping 30 the machines frequently to replace empty bobbins with full ones, and a characteristic feature of my invention is to enable a larger bobbin to be used for the under thread. The reels for the under thread in 35 machines I am at present using in my factory, contain about 35 to 40 yards of No. 40 cotton, but according to my present improvement, I so arrange the shuttle, that it will contain five, ten or fifteen times as 40 much (or more) thread of similar gage, thus effecting a very considerable saving of labor because the reels will only require changing once or twice a day, against a dozen times a day.

45 My invention may be advantageously employed in machines in which the shuttles have continuous rotary movements, and in what are known as rotary shuttle machines also in machines in which the shuttles have 50 reciprocating rotary movements and which are known as oscillating shuttle machines. My improvements though applicable for both types of machines will be more par-

ticularly described in connection with the latter.

In existing machines, the shuttle rock shaft below the cloth plate (of the bed) 55 upon which the material to be sewed rests, is journaled in such a position in proximity to the underside of the cloth plate or work 60 plate, that there is no room to permit of a larger reel for the under thread to be used than that at present employed, and the problem to be solved therefore is, how to apply 65 a larger reel for the under thread without in any way altering the position of the said shuttle rock shaft, or the bearings in which it is journaled.

My invention is characterized by the feature that the point about which the shuttle 70 oscillates (or the point about which it rotates in rotary shuttle machines) is eccentric to the axis of the shaft which imparts to the said shuttle its motion, that is to say the point about which the shuttle oscillates 75 (or rotates) is below the axis of the said driving shaft, and at a greater distance from the under side of the cloth plate or work plate than the shaft is. This enables the 80 shuttle driver to have a longer radius than in existing machines, so that the shuttle itself and the reel for the under thread which is contained within a cavity in the shuttle, can be considerably larger than hitherto.

The invention will be understood from 85 the following description reference being had to the accompanying drawings, in which:-

Figure 1 is a partial sectional side elevation of an oscillating shuttle sewing machine embodying the present invention.

Fig. 2 is a partial front end view of the same with certain parts removed for clearness.

Fig. 3 is a partial front elevation of the 95 same machine showing the shuttle in position to enter the loop of the needle thread.

Fig. 4 is a partial front elevation showing the shuttle in position to cast off the loop which has been carried around the bobbin case so that the lower thread has become 100 engaged by the needle thread.

Figs. 5 to 18 represent views of parts of the machine, detached from the residue; Figs. 5 and 6 being a sectional elevation and 105 face view of the crank arm at the end of the

rock shaft; Figs. 7 and 8 a vertical section and face view of the boss which is fixed eccentrically in relation to the rock shaft; Figs. 9, 10 and 11 a vertical section of the 5 shuttle driver a face view thereof and a vertical section showing the right and left hand portion; Figs. 12, 13, and 14 a vertical section of the shuttle a face view thereof and a vertical section showing the reverse 10 half to Fig. 12; Figs. 15 and 16 a face view and a vertical section of the shuttle race and its housing; and Figs. 17 and 18 a cross section and face view of the bobbin case.

Figs. 19 and 20 are diagrammatic views. 15 The general form of the sewing machine represented in these drawings, does not differ from that of many shuttle machines in common use, there being a bed plate 1, a strong arm (not shown) to support the needle bar 3 above the cloth plate or work plate 4, and a driving shaft extending through the said arm to drive the needle bar. The needle bar 3 is arranged to slide up and down in the head 2 of the needle arm, and motion 20 is transmitted to the needle bar from the driving shaft by suitable mechanism. The under thread which is interlooped with the needle thread to form the stitch is carried by an oscillating shuttle 7 which is caused 25 to oscillate in a stationary shuttle race 8 by means of an oscillating shuttle driver 9 to which motion is imparted by the shuttle rock shaft 10 in the manner hereinafter described, such rock shaft being arranged below the 30 cloth or work plate 4 of the machine. The shuttle consists as usual of three principal parts namely the circular body part having a cavity 7^a fitted with a central pivot 11 upon which the bobbin case 12 is mounted 35 by means of its central tubular shank 13 and the beak 14. The bobbin 15 which is contained within the bobbin case 12 is made in the form of a spool, and is similar to ordinary spools except that it is of larger 40 diameter, and the cavity 7^a in the shuttle is adapted to receive this bobbin case 12 with the bobbin contained inside it, the bobbin case being held in place by means of a spring latch 16. The office of the beak 14 is to enter 45 the loop of the needle thread presented by the needle and carry it around the bobbin case so that the lower thread becomes engaged by the needle thread, after which the needle thread is drawn up by the vibrating 50 arm of the take up. The shuttle driver 9 has two horns 17, 18 one of which bears against the butt of the shuttle 7 when driving it forward, and the other acts to drive the shuttle backward. The general manner 55 of looping the needle and shuttle threads to form the stitch is similar to many sewing machines in common use and so also is the manner of carrying the shuttle.

The circular shuttle race 8 is contained 60 within the housing 19 which is fixed station-

ary to the machine by set screws 19^x, the said race forming a reinforcement or lining for the housing. This race is constructed with an internal peripheral groove 20 to receive and guide the rim of the shuttle, and with 70 an external flange element 21 by which this race is secured in operative position in the housing 19 by screws 22 in threaded engagement with the housing. By unfastening the screws 22, the circular shuttle race should it 75 become worn, can be removed, and replaced by a new one. It will thus be seen that there is no wear on the housing which remains intact during the whole life of the machine, and any wear comes directly upon the lining 80 or race 8 which can be readily removed and replaced by a new one whenever required at small cost. If desired however the lining 8 can be dispensed with, and the housing 19 be made to form the shuttle race.

Fixed to the end of the machine adjacent to the shuttle rock shaft 10 is a circular boss 23. This is fixed eccentric to the axis of the said rock shaft 10, so that the major part of the said eccentric 23 shall lie below 90 the shaft 10. Upon this boss 23 which is turned true, I mount an annular strap 24 from which projects a radial arm 25 having integral therewith the oscillating shuttle driver 9. The said annular strap 24 which carries the driver 9 by the radial arm 25, is bored true so that it can freely oscillate upon the boss 23, and from one of these parts (preferably the connecting arm 25) projects a short stud or pin 26 upon which is mounted 100 an antifriction roller or sleeve. The said circular boss which as aforesaid is mounted eccentrically in relation to the axis of the rock shaft 10 has a hole 27 in it to form a clearance for the end of the shaft 10 to pass 105 through, and the extreme end of the shaft 10 carries a crank arm 28 which projects a little beyond the said boss 23. The crank arm has a tubular thickened portion 30 which fits on to end of the rock shaft and is 110 secured thereto by a pin 29. This crank arm 28 has a radial slot 31 at the end which engages the aforesaid antifriction roller on the pin or stud 26, so that an oscillating 115 movement is imparted to the oscillating shuttle driver 9 by the crank 28. The crank being fixed to the rock shaft 10 as aforesaid oscillates about the axis of the shaft 10 and imparts its oscillation to the shuttle driver 9 which oscillates upon the axis of the eccentrically-set boss or disk 23, which is fixed 120 securely in position to the bed plate by screws 32 passed through holes in the boss and the slot 31 in the crank 28 permits of the pin 26 having a free play therein. It 125 will accordingly be understood that the axis upon which the shuttle driver 9 oscillates is below the axis of the rock shaft 10 and at a greater distance from the under side of the cloth plate 4 than the rock shaft 10 is, and 130

this enables the oscillating shuttle driver 9 to have a longer radius than the radius of shuttle drivers in existing machines so that a larger shuttle and a larger bobbin and 5 bobbin case contained within the cavity in the shuttle, can be used.

The shuttle driver consists of the annular strap or sleeve 24 and the radial arm 25 with the pin 26, the said arm having the 10 two horns 17 and 18, these horns being located in a plane which is clear of the strap 24. One of these horns bears against the butt of the shuttle, when driving it forward, and the other horn acts to drive the 15 shuttle back.

Hitherto in oscillating shuttle machines the loops of the needle thread have frequently been carried around the bobbin case by a shuttle movement of only half a circle 20 or even less, so that it was necessary to employ a cast over guide or some equivalent device to direct the loops of the needle thread over or past the center of the bobbin case when they were carried forward by 25 the shuttle, and this cast over movement imposed a considerable strain on the needle thread which detracted in a measure from the capacity of the machine to operate when fine gage or weak thread is used. According 30 to my invention this disadvantage is entirely overcome by arranging the axis 34 of the rock shaft 10 and the axis 33 of the boss 23 in a plane passing through the middle of the vibrations of the crank arm 35 28 and the pin 26 of the shuttle driver or thereabouts. The position of boss 23 below the shuttle rock shaft 10 enables the pin 26 to be rocked through an arc of greater 40 extent than that of the crank arm 28 so that the curves described thereby intersect each other. This will be understood by reference to Figs. 19 and 20 in which the 45 arc described by the pin 26 as represented by the dotted line 40, 41, 42 is of much greater angular extent, than the arc described by the arm 28 appertaining to the 50 rock shaft 10 as represented by the dotted line 40, 43, 42. The movement of the shuttle driver pin 26 and consequently the shuttle 55 movement is therefore considerably more than half a circle, and the loops of the needle thread are carried over and past the center of the bobbin case, so that the loops slip off the beak 14 of the shuttle automatically and are drawn up by the take up 60 without the use of a cast off guide at all. Fig. 3 shows the position of the beak 14 of the shuttle when about to enter the loop of the needle thread, and be driven forward by the shuttle driver, and Fig. 4 shows the 65 position of the said beak 14 when it has carried the loop around the bobbin case and is ready to cast off its loop, whereupon the shuttle is driven backward so that its beak 14 comes again into the position shown

in Fig. 3. When the crank arm 28 is in the position shown in Fig. 19, the beak 14 of the shuttle is in the act of engaging the needle thread as shown in Fig. 3, and when the crank arm 28 is in the position shown 70 in Fig. 20, the beak 14 of the shuttle is in the act of throwing off the thread as shown in Fig. 4.

The invention can be used as an attachment to be applied to existing machines, or 75 it can be applied to new machines, its special duty being to enable the shuttle to carry a very much larger quantity of under thread so as to reduce the frequency with which the empty spools in shuttles have to be 80 changed and substituted by filled ones.

I declare that what I claim is:—

1. A sewing machine having in combination a shuttle driver so pivotally supported at the point upon which it oscillates or rotates, as to be eccentric to and below the axis of the operating shaft and thus be at a greater distance from the underside of the work plate, than the shaft is, in order to permit of it being of larger dimensions 85 and enable a larger quantity of under thread to be contained within the shuttle, a circular shuttle race fixed concentrically with respect to the axis of the shuttle driver, a shuttle running on the said race, and a bobbin supported within the said shuttle. 90

2. In a sewing machine, the combination with an operating shaft, of a shuttle driver mounted upon an axis which is below the axis of the said shaft with the specific object of giving more space to enable a larger shuttle and bobbin to be used than would otherwise be possible, adjacent arms on the said shaft and shuttle driver respectively, a pivot connecting the said arms so that the 100 motion of the shaft is transmitted to the shuttle driver, a circular shuttle race supported concentric to the axis of the driver but eccentric to the axis of the operating shaft, and a shuttle and bobbin contained 105 within the said race.

3. In a sewing machine, the combination with an operating shaft, of a circular boss fixed at or near the end of the machine and whose axis is eccentric to and below the axis 115 of the shaft, an annular strap mounted freely upon this boss so that it can be moved about the same, from which strap projects a radial arm carrying the shuttle driver, an arm fixed on the shaft adjacent to the said 120 driver arm, and a pivot connecting the said arms so that the motion of the operating shaft is transmitted to the shuttle driver which moves upon the axis of the boss.

4. In a sewing machine, the combination 125 with an operating rock shaft, of a shuttle driver mounted upon an axis which is below the shaft, adjacent arms on the said shaft and shuttle driver respectively and a pivot connecting the said arms whereby an oscil- 130

lating motion is transmitted to the shuttle driver from the rock shaft, but the said driver (and consequently the shuttle) is caused to move a greater angular distance than the oscillating shaft, by reason of the axis of the driver being eccentric to that of the shaft.

5. In a sewing machine, the combination with an operating shaft of a fixed boss or 10 disk whose axis is eccentric to and below the axis of the shaft, and a shuttle driver comprising an annular strap or sleeve, a radial arm projecting outwardly thereon, a pin on the arm, and horns located in a plane 15 which is clear of the strap.

6. In a sewing machine, the combination of an operating shaft, of a circular boss whose axis is eccentric to and below the axis of the operating shaft, said boss having a 20 hole therein to produce a clearance aperture through which the end of the shaft passes; and a shuttle driver mounted on the boss.

7. In a sewing machine, the combination with an operating shaft of a shuttle and 25 shuttle driver whose axis is eccentric to and below the axis of the shaft, a circular housing mounted concentrically with respect to the axis of the shuttle and driver, and a circular shuttle race mounted within the hous-

ing for the shuttle to run in, the said race 30 being arranged to be readily removable from the housing so that it can be replaced by a new one.

8. In a sewing machine, the combination of a work plate; a shuttle operating shaft 35 located below and at a short distance therefrom; a relatively large shuttle, the axis whereof is eccentric to and below that of the shaft; a shuttle support; a shuttle driver; and means carried by the shaft for 40 actuating the driver.

9. In a sewing machine, the combination of a work plate, a shuttle operating shaft; a shuttle support having its axis located eccentrically to that of the shaft; a shuttle 45 carried by said support below said work plate; a shuttle driver; and means attached to the shaft and coöperating with the shuttle driver to actuate the same.

In witness whereof, I have hereunto 50 signed my name this 17th day of January, 1921, in the presence of two subscribing witnesses.

JAMES MARSDEN.
